ENGLAND

MOLD FOR CASTING PRINTERS' FURNITURE

Application filed April 26, 1930, Serial No. 447,498, and in Great Britain January 29, 1930.

The present invention has relation to molds for casting printers' furniture or "clumps", more particularly the elongated skeleton strips utilized by printers as spacing media, the present invention having for its object to provide for the particularly expeditious and efficient manufacture of such strip.

According to the present invention we provide a two-part mold, one part of which is 10 slidable in relation to the other or complementary part, said two-part mold incorporating in combination a plurality of protruding matrices on the one part adapted to cooperate with a longitudinal channel in the other or complementary part, means for filling the interior of the mold with the fluid casting metal, and mechanical means for slidably displacing one part in relation to the other for removing the skeleton strip. The 20 one part of the mold may incorporate a plurality of channels of differing transverse dimensions and the other or complementary part a corresponding plurality of matrices co-operable with the said channels, and, further, a closure member may be adapted for association with any particular matrix for closing the channel for obtaining a predetermined length of skeleton strip.

In order that this invention may be clearly 20 understood and readily carried into practice, reference may be had to the appended explanatory sheet of drawings, upon which:—

Figure 1 is a plan view of the base portion 35 of the mold incorporating the molding channels and operating lever.

Figure 2 is a plan view of the slidable closure member illustrating the hoppers through which the channels are fed and the trunnions which co-operate with the operating lever.

Figure 1 is a transverse section taken on the line 3—3 of Figure 1.

Figure 4 illustrates the device shown in Figure 1 in end elevational aspect looking in the direction of the arrow 4.

Figure 5 is a longitudinal section taken on the line 5—5 of Figure 2, illustrating particularly the matrices and the hopper, and

Figure 6 is a transverse section taken on the line 6—6 of Figure 2.

Figure 7 is a longitudinal section illustrating the mold components shown in Figures 1 and 2 aggregated together for use. 55

Figure 8 is a transverse sectional elevation through the aforesaid aggregation.

Figure 9 illustrates the application of the mold to a support whereby it is maintained at an inclination to assist in the filling operation. 60

Figure 10 is an elevational view of the support *d* shown in Figure 9.

Figure 11 is a perspective view of a section of skeleton strip manufactured by the present 65 mold, and

Figure 12 is a perspective view of one of the closure members hereinafter referred to for limiting the effective length of a molding channel. 70

In a convenient embodiment of the present invention the mold comprises a flat base *a* (see Figure 1) having one, two, three or more channels *a1* of rectangular section and elongated formation. Where a plurality of 75 channels are utilized as shown these have a differing transverse measurement or section.

The base is provided with an inwardly directed flange *b* to constitute a channel *b1* (see particularly Figure 3) wherein a closure 80 plate *c* (Figure 2) is adapted to slide. Clamps *a4* are adapted to hold the closure plate at that extremity remote from the flange *b*. *c5* is a handle provided upon the closure plate. Provided on the under face of the 85 closure plate *c* are a plurality of spaced matrices *c1* (see Figure 5) adapted to co-operate with the channel or channels *a1* in the base *a*. Each matrix may be of substantially rectangular block-like formation 90 involving four slightly convergent walls or faces as shown and the bases of the matrices are adapted to slide along the bases of the channels. The closure plate *c* is provided with a depending flange *c2* adapted to close the extremities of the channels *a1* the remote extremities being closed by the fixed bar *a2* 95 (Figure 3). One, two or more hoppers *c3* according to the number of channels are provided through which the molten metal may 100

be passed when the closure plate is fully home. The closure plate *c* is provided with trunnions *c4* on its upper face with which the limbs of a U-shaped operating handle 5 *a3* pivoted to the base *a* are adapted to co-operate.

Figure 9 illustrates a frame or stand device *d* for supporting the mold at an inclination. In this respect it will be noted that 10 the hoppers *c3* are designed for such inclination, and when the molten metal is poured into the mold the filling thereof is assisted by the gravitation of the metal along the channels. Such a supporting frame however is not indispensable inasmuch as the mold if desired may be used in a horizontal position and the hoppers *c3* appropriately adapted for receiving the molten metal whilst the mold is in such a position. Figure 12 15 illustrates a closure member *e* adapted to be applied to one of the matrices *c1* for the purpose of closing off a section of the channel. In this manner any predetermined length of the skeleton frame *f* illustrated in Figure 11 20 may be obtained.

In operation the closure plate *c* with its 30 one or more series of matrices is slid home in relation to the base plate *a* by means of its handle *c5* and the clamps *a4* afterwards tightened. The flange *c2* closes the extremities of the channels *a1* and these said channels are effectively closed superficially by the plate *c* which engages the flange member *b*. The molten metal is poured into the channel, or 35 the desired channel if a plurality are present, by way of the hopper or hoppers *c3*, and the metal allowed to gravitate or flow along the channel or channels between the matrices to constitute the skeleton strip illustrated in 40 Figure 11 used by the printer as spacing media. The metal having set, the clamps *a4* are released and the handle member operated to displace the closure plate by means of the cam parts *a5* engaging the trunnions *c4* bringing 45 the skeleton strip now constituted away from the channels and leaving it in position upon the protruding matrices from which it can be readily removed by hand or with the aid of a simple tool. When a length of skeleton strip is required short of the overall length 50 of the channel the closure member *e* is applied to one of the matrices in the manner shown in Figures 7 and 8. This closure member exactly fits the matrix in the channel and 55 thereby limits the effective length of the said channel during the molding or casting operation.

We claim:

1. A mold comprising a base plate having 60 a channel opening through the top and an end thereof, a closure plate adapted to be removably superimposed upon said base plate to close the upper side of said channel, means carried by the closure plate for cooperation 65 with the base plate to close the open end of

said channel when the closure plate is superimposed upon the base plate, said closure plate having an opening formed therethrough for the introduction of molten metal into the channel, a projection on the under side of said cover to extend into the channel of the base plate, and a member adapted to be disposed in said channel to vary the effective length of the channel. 70

2. A mold comprising a base plate having 75 a channel opening through the top and the front end thereof and closed at its rear end, a closure plate adapted to be superimposed upon said base plate to close the upper side of said channel, means carried by said closure plate for cooperation with the base plate to close the front end of said channel, means 80 forming a guideway carried by the base plate to receive marginal portions of the closure plate to hold the latter operatively superimposed upon the base plate, trunnions projecting laterally from the closure plate, and a lever element pivoted to the base plate for cooperation with said trunnions to slide the closure plate into said guideway. 85

JOHN EDWARD PHILLIPS.
ALBERT GEORGE THACKERAY.
